UNITED STATES PATENT OFFICE.

HENRY APPEL, OF PLAINVIEW, MINNESOTA.

BOX-COVER FASTENER.

Application filed October 27, 1922. Serial No. 597,321.

To all whom it may concern:

Be it known that I, HENRY APPEL, a citizen of the United States, residing at Plainview, in the county of Wabasha and State of Minnesota, have invented certain new and useful Improvements in Box-Cover Fasteners, of which the following is a specification.

This invention relates to new and useful improvements in box cover fasteners.

10 One object of my invention is to provide simple and efficient means which may be employed as a permanent fastener for the box lid or cover, but which may be released by the operator to permit the removal of the

15 cover.

Other objects of my invention will appear as the nature of the same is better understood, reference being had to the accompanying drawings forming a part of this application in which—

Figure 1 is a side elevation illustrating the application of my invention.

Figure 2 is a reverse or bottom plan view of the cover.

25 Figure 3 is a central longitudinal sectional view of Figure 1.

Figure 4 is an end view and,

Figure 5 a detail perspective view of one of the fastening bolts.

30 Referring to the drawings for a more particular description of my invention and in which drawings like parts are designated by like reference characters throughout the several views, A designates a rectangular

35 box of any desired type, shape or size, B the lid or cover and C my improved fastening means, as a whole. The cover B is provided on its bottom face at opposite ends with the transverse cleats or strips 1 which, as shown,

40 fit against the end walls 2 of the box, the purpose of which will be apparent.

Depending loop shaped clips 3 are carried by the strips 1 and the latter formed in

45 their bottom edges with central notches or recesses 4 to accommodate said clips. The end walls 2 of the box are also provided with cross bars or strips 5 on which the strips 1 rest and said strips 5 carry the vertically disposed fastening bolts 6 formed at their

50 upper ends with the outwardly and downwardly curved or bent heads 7 adapted to hook over the clips 3 when the lid or cover is mounted in position. The lower ends of the fastening bolts 6 project below the cross

bars 5 and are provided with coil or helical 55 springs 8 which prevent casual disengagement of the bolts with said clips.

The upper end of the coil springs 8 bear against the washers which fit against the bottom edges of the cross bars 5 while the 60 lower ends of said spring seat on the nuts 10 screwing on the lower threaded ends of the fastening bolts.

Other smaller or secondary coil springs 11 are arranged at right angles with the 65 fastening bolts 6 with their inner ends seating in corresponding recesses or sockets 12 formed in the outer faces of the end walls 2 of the box and their outer ends bearing against the upper ends of the fastening bolts. 70 These springs assist in holding the upper ends of the fastening bolts against casual disengagement with the clips.

Through the use of my invention, the box lid or cover may be quickly applied to the 75 box and cannot become unfastened without first projecting the fastening bolts against the tension of the coil springs 8 and then turning the bolts to disengage the hooks 7 with the clips.

The lower ends of the fastening bolts are provided with transverse openings a for the 80 purpose of sealing the attachment by small wires (not shown) which are inserted through the bolts and the clips.

From the foregoing description taken in connection with the drawings, it is thought that the construction, operation and advantages of my invention will be readily understood without requiring a more extended explanation.

Various changes in the form, proportions and minor details of construction may be resorted to without departing from the principle or sacrificing any of the advantages 95 of my invention as defined in the appended claims.

Having described my invention, what I claim as new and desire to secure by Letters Patent, is:—

1. A box cover fastener comprising clips depending from the cover and spring retracted fastening bolts carried by the box and provided at their upper end with hooks adapted to engage said clips when the cover is in position, and other smaller or secondary springs arranged at right angles with the fastening bolts with their outer ends engag-

ing the latter, said last mentioned springs assisting in preventing casual disengagement of the fastening bolts with the clips.

2. A box cover fastener comprising loop-shaped clips depending from opposite ends of the cover and vertically disposed spring retracted fastening bolts carried by opposite ends of the box and provided at their upper ends with outwardly bent hooks adapted to hook over or engage said clips and other smaller springs arranged in a horizontal plane with their outer ends bearing against the upper ends of the fastening hooks.

3. A box cover fastener comprising cross bars at the ends of the cover engaging the end of the box, clips carried by and depending from said cross bars, other cross bars secured to the end walls of the box and providing a support for the first mentioned cross bars, vertically disposed fastening bolts

carried by said second mentioned cross bars and provided at their upper ends with outwardly bent hooks adapted to engage said clips, coil springs disposed around the lower ends of said fastening bolts for normally holding the latter in retracted or clip engaging position, nuts screwing on the lower threaded end of said bolts and other smaller springs arranged with their inner ends engaging the end walls of the box and their outer ends bearing against the upper ends of the fastening bolts, said smaller springs co-operating with said first mentioned springs in holding the hooks of the fastening bolts against casual disengagement with the clips. 25 30 35

In testimony whereof I have affix my signature.

HENRY APPEL.
